DESIGN FOR A BRIDGE

Joseph B. Strauss, San Francisco, Calif.

Application August 31, 1937, Serial No. 71,407

Term of patent 3½ years

To all whom it may concern:

Be it known that I, Joseph B. Strauss, a citizen of the United States of America, residing at San Francisco, in the county of San Francisco and State of California, have invented a new, original, and ornamental Design for a Bridge, of which the following is a specification, reference being had to the accompanying drawings, forming a part thereof.

Fig. 1 is a top plan view of the bridge showing my new design;

Fig. 2 is an end view thereof; and

Fig. 3 is a side elevation of my bridge.

I claim:

The ornamental design for a bridge substantially as shown.

JOSEPH B. STRAUSS.
